[57] CLAIM

The ornamental design for a chair, as shown and described.

DESCRIPTION

FIG. 1 is a perspective view from the front and to one side of the chair.

FIG. 2 is a side elevational view of the chair of FIG. 1, the other side of the chair being a mirror image of this view except for also having the control levers shown in FIG. 1.

FIG. 3 is a front elevational view of the chair of FIG. 1.

FIG. 4 is a rear elevational view of the chair of FIG. 1.

FIG. 5 is a top plan view of the chair of FIG. 1.

FIG. 6 is a perspective view from the front and to one side of an alternate embodiment of the chair in which the chair does not have arms.

FIG. 7 is a side elevational view of the chair of FIG. 6, the other side of the chair being a mirror image of this view except for also having the control levers shown in FIG. 6.

FIG. 8 is a front elevational view of the chair of FIG. 6.

FIG. 9 is a rear elevational view of the chair of FIG. 6; and, FIG. 10 is a top plan view of the chair of FIG. 6.
